United States Patent Office.

WILLIAM EBERHARD, OF AKRON, OHIO, ASSIGNOR TO HIMSELF AND
A. P. BALDWIN, OF SAME PLACE.

Letters Patent No. 73,785, dated January 28, 1868.

IMPROVED WASHING-MACHINE.

The Schedule referred to in these Letters Patent and making part of the same.

TO ALL WHOM IT MAY CONCERN:

Be it known that I, WILLIAM EBERHARD, of Akron, in the county of Summit, and State of Ohio, have invented a new and useful Improvement in Washing-Machine; and I do hereby declare that the following is a full, clear, and exact description thereof, which will enable those skilled in the art to make and use the same, reference being had to the accompanying drawings, forming part of this specification, in which—

Figure 1 represents a side elevation of my improved washing-machine.

Figure 2 is a cross-section, taken in the line $x-x$, fig. 1.

Figure 3 is a cross-section, taken in the line $y-y$, fig. 1.

Figure 4 is a partial under side view.

Similar letters of reference indicate corresponding parts.

This invention relates to an improved washing-machine, and consists in a device for attaching to an ordinary washing-tub, which device consists of two corrugated rollers, one of which has a slow rotary motion, and the other a reciprocating motion, between which rollers the clothes pass and are rubbed to discharge the dirt and cleanse them thoroughly, as hereinafter particularly described.

A represents a strong wooden frame, as long as necessary to extend across a wash-tub, to be fastened on the upper edge by a set-screw, a , on the end, as shown in fig. 1. A corrugated roller, B, made of wood or any suitable hard substance, runs lengthwise on the upper side of the frame A, set upon a shaft, b , made of gas-pipe or an iron rod, on one end of which shaft is a pinion, c , that takes motion from a worm, d , on a crank-shaft, e . Over the roller B is placed another corrugated roller, C, covered with rubber or hard cord, which roller is hung between two vibrating frames, g g , at its ends, one of which frames is connected by a pitman, h , with a crank-shaft, k , geared to the crank-shaft e , and so arranged that the roller C has a reciprocating movement over the roller B, while it rotates by turning the crank m on the shaft e . The vibrating frames g g are connected by a rod, n , that is attached at one end to a hand-lever, p , and so arranged that by the action of the lever the upper roller C may be lifted easily from the lower roller B, to introduce one end of the clothes to be washed. The frames are so pivoted that the upper roller can rise or fall easily, according to the bulk of clothing passing between the two rollers. Guards q q are placed on each side of the lower roller B.

The operation is as follows: The clothes being in the tub with suds, as usual, one part is placed between the rollers B C, when, by turning the crank m , the lower roller A will turn and carry the clothes over with it, while the upper roller, C, will reciprocate and produce a rubbing motion, whereby the clothes will be cleansed by the combined action of the two rollers, in a manner similar to rubbing with the hands, and with trifling manual exertion.

Having described my invention, I claim as new, and desire to secure by Letters Patent—

1. The washing-machine constructed as described, and consisting of the rollers B C, frame A, shaft b , vibrating frames g g , pitman h , crank-shaft k , shaft e , crank m , worm d , pinion c , fly and gear-wheels, lever p , and rod n , all arranged and operating as described, and for the purpose specified.

2. In combination with the vibrating frames g and roller C, I claim the lever p and rod n , substantially as and for the purpose set forth.

3. In combination with roller B, I claim the guards q , substantially as set forth.

WILLIAM EBERHARD.
